CLAIM

The ornamental design for a display screen with virtual three-dimensional vehicle icon or display system with virtual three-dimensional vehicle icon, as shown and described.

DESCRIPTION

FIG. 1 is a front view of a display screen with virtual three-dimensional vehicle icon showing my new design in a front perspective orientation;

FIG. 2 is another front view thereof, showing a rear orientation thereof;

FIG. 3 is another front view thereof, showing a front orientation thereof;

FIG. 4 is another front view thereof, showing a rear orientation thereof;

FIG. 5 is another front view thereof, showing a left side orientation thereof;

FIG. 6 is another front view thereof, showing a right side orientation thereof;

FIG. 7 is another front view thereof, showing a top orientation thereof;

FIG. 8 is another front view thereof, showing a bottom orientation thereof;

FIG. 9 is a front view of a display system with virtual three-dimensional vehicle icon shown in a front perspective orientation, the virtual three-dimensional vehicle icon being the same design as shown in FIGS. 1-8;

FIG. 10 is another front view thereof, showing a rear orientation thereof;

FIG. 11 is another front view thereof, showing a front orientation thereof;

FIG. 12 is another front view thereof, showing a rear orientation thereof;

FIG. 13 is another front view thereof, showing a left side orientation thereof;

FIG. 14 is another front view thereof, showing a right side orientation thereof;

FIG. 15 is another front view thereof, showing a top orientation thereof; and,

FIG. 16 is another front view thereof, showing a bottom orientation thereof.

The broken lines showing various features of the vehicle icon form no part of the claimed design. In FIGS. 1-8, the outermost broken line represents a display screen which forms no part of the claimed design. In FIGS. 9-16, the

(Continued)

outermost broken line represents a portion of a field of view for a visual display system and forms no part of the claimed design.
